UNITED STATES PATENT OFFICE.

JUSTUS DIEHL, OF NEW YORK, N. Y.

PIANO SOUNDING-BOARD.

SPECIFICATION forming part of Letters Patent No. 280,362, dated July 3, 1883.

Application filed August 11, 1882. (No model.)

To all whom it may concern:

Be it known that I, JUSTUS DIEHL, of New York, in the county and State of New York, have invented a new and useful Improvement 5 in Sounding-Boards for Piano-Fortes, of which the following is a full, clear, and exact description, reference being had to the annexed drawings, forming part of this specification.

My invention belongs to the class of pianos 10 in which a sound-chest is formed of two boards secured to opposite sides of a supporting-frame, and provided with a single opening for the escape of the sound.

My invention consists in forming such a 15 sound-chest with the opening made in the main sound-board, extending across the same from side to side, or formed wholly in said board, and in combining with the sound-boards a number of sound-posts, which are 20 secured to the inner surfaces of the sound-boards in such manner that the boards may be drawn inward tightly against the ends of the posts, whereby the boards shall always vibrate in perfect unison with each other.

25 In the drawings, Figure 1 is a front elevation of my invention as adapted to upright pianos. Fig. 2 is a vertical section on line *x x*, Fig. 1; and Fig. 3 is a horizontal section of the same on line *y y*, Fig. 1, showing the opening in the 30 board formed near its center instead of at one edge.

Heretofore a sound-chest for a piano has 35 been formed with two sound-boards, the upper one of which, together with the end of the chest, is cut away at one corner to form an opening for the escape of the sound. An open sound-chest has also been formed with two sound-boards, one of which is supported above the strings by means of standards or 40 posts, to which it is secured by screws. Now, the object of my invention is to provide a sound-chest having the opening extended across the main sound-board from side to side or formed wholly in said sound-board, with 45 which shall be combined a number of sound-posts adapted to draw the sound-boards or the sound-board proper and the back or bottom of the chest inward toward each other, and to hold them tightly in contact therewith, to the 50 end that the two boards shall be adapted to vibrate in perfect unison with each other.

A indicates the sounding-board, which may be constructed with an opening, B, near its center, or with an opening, C, formed by cutting away its upper edge on a curved line.

The box D, to which the sounding-board is secured, is completely closed at the sides and back, so that there shall be no opening leading therein, except the opening in the said board. The inner surfaces of the sounding-board and the back of the box are provided with ribs, as shown. 60

Between the sounding-board and the back of the box are provided one or more posts, E, which are provided at their ends with a screw-threaded bolt, e, and secured in position by means of nuts e', screwing on the ends of the bolt, which project through perforations in the board and back. By screwing up the nuts the back and the sounding-board will be firmly 65 connected together, so as to vibrate in unison when the chords are struck. The sounding post or posts, instead of being placed in contact with the inner surfaces of the board and back, may be secured between corresponding 70 ribs on the board and back, and they may also be secured in position by means of screws driven into their ends from outside the box.

In a grand piano, owing to the horizontal position of the sounding-board, the posts may 80 be secured in place without the use of the expedients above described. When used in a grand piano, the board is to be provided with an opening near the center, as shown in Fig. 3, instead of at one edge, in order that the 85 hammer mechanism may be arranged entirely outside the box.

Having thus described my invention, what I claim, and desire to secure by Letters Patent, is—

The combination of the back board and sound-board, constructed and arranged as described, the intervening supporting-frame, to which the back and sound-board are secured to form a close chamber, and the sound-posts 90 arranged between the boards, and having bolts passing through them and provided with nuts for securing them to the boards, whereby the latter may be drawn inward and held under tension against the intervening frame, and 95 whereby the said tension may be regulated according to natural changes in temperature, substantially as specified.

JUSTUS DIEHL.
